ALEXANDER BLACKMAN, OF PENSACOLA, FLORIDA, ASSIGNOR TO PATENT FINANCE
AND HOLDING COMPANY, A CORPORATION OF FLORIDA

ROTARY GAS ENGINE

Application filed June 22, 1928. Serial No. 287,577.

This invention relates to an air cooled rotary motor, the general object of the invention being to provide a stationary cylindrical member carrying the inlet valves and reciprocating pistons, with means for introducing an explosive mixture into the member and a rotating casing of substantially oval shape and having opposing portions always in contact with the walls of the cylindrical member so that its remaining portions form with the cylindrical member chambers of substantially crescent shape, with cam means for causing the pistons or abutments to enter such chambers and divide the same into intake, compression, exhaust and firing portions during the rotation of the casing, with spark plugs and exhaust means associated with the casing.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation of the improved motor, with parts in section.

Figure 2 is a longitudinal sectional view thereof.

Figure 3 is a transverse sectional view.

Figure 4 is a fragmentary side view showing the exhaust means.

Figure 5 is a similar view showing the spark plugs.

Figures 6 and 7 are views showing a pair of the blades for the pistons.

Figure 8 is a view of one of the packing plates arranged at each end of each piston.

In these views, the numeral 1 indicates a stationary hollow shaft which has one end closed by a plug 2 and its other end is adapted to be connected with a carburetor or other supply of explosive mixture. The numeral 3 indicates the stator which is of circular or cylindrical shape and of hollow construction

and this stator is keyed or otherwise fastened to the hollow shaft. Ports 4 are formed in the inner circumference of the stator and in the shaft so that the explosive mixture can pass from the shaft into the stator.

The casing A is of substantially oval shape in cross section with its side portions contacting with parts of the stator at all times during the rotation of the casing, with its end portions forming chambers between said portions and portions of the stator, these chambers being of substantially crescent shape. The casing is rotatably mounted on the shaft, anti-friction bearings 5 being placed between the bearing parts and packing means 6 being arranged between the bearing parts to prevent leakage of oil. The casing comprises the end plates 7 which are formed with the strengthening ribs 8 and the substantially oval-shaped part 9 formed with the fins 10, with the inner and outer hollow cam plates 11 and 12 placed between the end plates and the member 10, these parts being fastened together by the bolts 13. Each pair of the cam plates forms a cam groove 14 and each cam plate is provided with an outwardly extending flange 15, the flanges of each pair of plates forming a cam track for the rollers of the pistons, as hereinafter to be described.

The flanges of the outer cam plates 12 form annular air chambers 16 through which air can enter through the ports 17 formed in the end plates and the flanges of the inner plates 11 forming annular oil chambers 18, one oil chamber being connected with a supply of oil by means of the pipe 19 which is connected with said chamber by the port 20 and the other oil chamber is connected with the return oil pipe 21 by the port 22. As will be seen, these oil pipes 19 and 21 are arranged in the hollow shaft 1. Rings 23 are placed between the cam plates and the end plates and the member 10, these rings occupying grooves formed in the parts to provide tight joints between the parts.

The stator 3 is formed with the radially arranged pockets 24 which extend longitudinally of the stator and pass through the ends thereof. A piston or sliding abutment 100

25 is arranged in each pocket and has the bearings 26 at its inner edge for the shaft 27, the ends of which pass through the grooves 14 and have the rollers 28 fastened thereto, these rollers engaging the cam tracks formed by the flanges 15 of the cam plates. Thus the pistons will be reciprocated in the stator as the casing revolves, due to the rotary movement of the cam plates with the 10 casing. These cam parts are so formed that the outer ends of the pistons will remain in contact with the interior walls of the casing throughout each revolution of the casing.

Ports 29 are formed in the walls of the oil 15 chambers 18 and communicate with the inner ends of the pockets 24 so that the oil can pass from one chamber through the pockets into the other chamber and then return to the source through the return pipe 21. The bearings 26 are formed with holes 26' so that the 20 oil passing through the pockets can lubricate the bearings.

Packing strips 30 are placed in grooves 25 in the side walls of each pocket and contact with the sides of the piston in the pocket and packing strips 31 are arranged in grooves 30 in the side walls of each piston and are pressed against the internal walls of the pocket by the springs 32 arranged in openings 33 in the pistons. These packing strips 30 and 31 prevent leakage between the sides of each piston and the walls of the pocket. A substantially L-shaped packing member 33 is placed at each end of each piston in slots 35 formed in the piston end and these members are pressed outwardly against the cam plates 12 by the springs 34 placed in holes in the piston end. A part of each member 33 engages a part of the lower edge of each piston 40 and the major part of each member 33 engages a part of the end of each piston, as is clearly shown in Figure 2. This major part is of forked construction, as shown in Figure 8, so that it will bridge the inwardly extending end portions of a longitudinally extending opening 35 formed in the outer portion of each piston, this opening extending through the ends of the piston.

Substantially L-shaped blades 36 are arranged in pairs in said opening, with the short arms extending into the inwardly extending portions of the opening and as shown in Figure 3, the short arm of each blade is of twice the thickness of the long arm so 55 that when the two blades are placed together, they will form a blade of substantially channel shape and of the same thickness throughout. The blades are pressed outwardly against the internal walls of the casing by the plungers 37 and the springs 38 arranged in the pockets 39 formed in the pistons. The outer ends of the plungers are formed of concave shape to receive portions 60 of a rocker strip 40 which is of semi-circular shape in cross section with its flat face en-

gaging the bottom of the blades 36. This arrangement will permit the blades to have individual movement and thus remain in contact with the internal walls of the casing during the rotation of the casing. The springs 70 38 and their plungers will act to force the blades outwardly against the internal walls of the member 9 and plungers 41 and their springs 42 engage the short arms of the blades and tend to force the blades against 75 the cam plates 12, these plungers and their springs being arranged in pockets 43 formed in the pistons. Thus the blades are tightly held against the walls of the casing.

A sectional packing ring 44 is arranged in 80 a groove at each end of the stator, the sections of these rings abutting the walls of the pockets and they are pressed against the cam rings 12 by the springs 45 arranged in pockets formed in the ends of the stator. 85 These rings 44 prevent leakage between the stator and the cam plates.

One of the end plates is formed with an extension 46 to which the member or element 90 which is to be driven is connected so that this element will rotate with the casing. An annular exhaust chamber 47 is connected with the other end plate of the casing and this chamber has its outer part closed by a cover plate 48 which is rotatably held in place by 95 the inner and outer rings 49 and 50, which are bolted to the walls of the chamber and arms 51 connect the ring 48 with a clamp 52 which engages a part of the hollow shaft 1. Thus this ring 48 is stationary while the parts forming the chamber 47 rotate with the casing. A plurality of exhaust pipes 53 communicate with the chamber 47 and are connected with the ring 48. A ring-shaped exhaust manifold 54 is bolted to the end plate 100 which carries the chamber 47 and pipes 55 connect the manifold with the chamber 47. A number of pipes 56 connect one portion of the casing through the member 9 with the exhaust manifold and a number of spark plugs 57 is carried by the casing, the spark plugs being arranged adjacent a flat side of the casing, with the exhaust pipes 56 arranged almost opposite the plugs. As 110 shown in Figures 4 and 5, the plugs and exhaust pipes are arranged in longitudinally extending rows on the casing.

As shown in Figure 1, I provide an oil pipe 58 which delivers the oil to the ports 59 in the cover plate 48, these ports passing 120 through the inner and outer edges of the plate so as to lubricate the edges of the plate which are engaged by the rings 49 and 50.

As shown in Figure 3, the pockets divide 125 the interior of the stator into a plurality of chambers and the explosive mixture enters these chambers through the ports 4 from the hollow pipe 1. A valve casing 60 is arranged in the stator adjacent each pocket, the casing opening out through the outer circumference 130.

of the stator and being in communication with the interior thereof through the port 61. A valve cage 62 is held in each casing by the nut 63 and a spring pressed valve 64 is carried by each cage, the spring 65 of which acts to hold the valve on its seat but permits the valve to open under the suction created by the revolving casing.

As shown in Figure 3, the stator, the casing and the pistons form an intake chamber I, an exhaust chamber E, a neutral chamber B, a firing chamber F and a compression chamber C. With the parts in the position shown in Figure 3 and with the casing rotating in an anti-clockwise direction, explosive mixture is being drawn into the chamber I through the valve from the interior of the stator, while the mixture in the chamber C is being compressed by the gradual restriction of said chamber due to the flattened part of the casing passing over the part of the stator and in order to provide spaces for the compressed mixture as the contacting part of the casing passes over that part of the stator in which the gas is being compressed, I form V-shaped recesses 66 in the exterior walls of the stator between each valve casing and the pocket in front of said casing and I also provide a chamber 67 between the two valve casings.

Thus as the flattened part of the casing passes over that part of the stator lying between two of the pistons, the explosive mixture will be compressed into the grooves 66 and chamber 67 and this mixture will expand into the chamber containing the spark plugs 57 as the flattened part passes beyond the grooves 66 and the chamber 67. Then the charge is fired by the explosion, as shown at F in Figure 3, and the gases acting against the piston forming the rear wall of the firing chamber and the flattened portion of the casing will give an impulse to the casing and thus cause it to revolve. The gas will continue to expand until one end of the casing comes over that part of the stator between the two pistons where the charge has been fired and then when that part of the casing containing the exhaust pipe 56 comes over said part of the stator, the gases will exhaust through the pipes 56 into the manifold 54 and from the manifold the gases will pass through the pipes 55 into the chamber 47 and escape from the chamber through the pipes 52.

From the foregoing it will be seen that a compressed mixture is fired each time the spark plug carrying part of the casing passes a piston so that a motor provided with five pistons, as shown in the drawings, will have five impulses for every revolution of the casing so that a motor of great power is provided. In other words, during the rotation of the casing about the stator, a charge of explosive mixture will be drawn into the space

between the stator and casing and a pair of the pistons and then this mixture will be compressed, then the compressed mixture will be fired and finally the exploded mixture will be exhausted.

The parts are oiled by the oil flowing through the inner parts of the pockets and contacting with the various parts of the pistons and other moving parts and the parts will be cooled by the air engaging the fins 10 and entering the chambers 16 through the ports 17.

It is thought from the foregoing description that the advantages and novel features of my invention will be readily apparent.

It is to be understood that I may make changes in the construction and in the combination and arrangement of the several parts, provided that such changes fall within the scope of the appended claims.

What I claim is:—

1. An internal combustion motor comprising a cylindrical stator of hollow construction, a casing enclosing the stator and revolving around the same, said casing being of oval shape with its sides contacting the stator and its end portions spaced from the stator and forming therewith crescent-shaped chambers, radially arranged pockets in the stator dividing the interior thereof into chambers, a piston slidably arranged in each pocket, cam means carried by the casing for reciprocating the pistons, means for introducing an explosive mixture into each chamber of the stator, valve means in each chamber of the stator for controlling the passage of mixture from the said chamber into the crescent-shaped chambers, the valves being opened by the suction created in the crescent-shaped chambers by the rotation of the casing, ignition means carried by the casing adjacent one flat side thereof and exhaust means carried by the casing adjacent the other flat side thereof.

2. An internal combustion motor comprising a cylindrical stator of hollow construction, a casing enclosing the stator and revolving around the same, said casing being of oval shape with its sides contacting the stator and its end portions spaced from the stator and forming therewith crescent-shaped chambers, radially arranged pockets in the stator dividing the interior thereof into chambers, a piston slidably arranged in each pocket, cam means carried by the casing for reciprocating the pistons, means for introducing an explosive mixture into each chamber of the stator, valve means in each chamber of the stator for controlling the passage of mixture from the said chamber into the crescent-shaped chambers, the valves being opened by the suction created in the crescent-shaped chambers by the rotation of the casing, ignition means carried by the casing adjacent one flat side thereof, exhaust means

carried by the casing adjacent the other flat side thereof and recesses formed in the circumference of the stator adjacent the valve.

3. An internal combustion motor comprising a hollow stationary shaft, a cylindrical stator fastened to the shaft, an oval-shaped casing enclosing the stator and rotatably supported on the shaft, said casing having its sides contacting the stator and its end portions spaced therefrom to form crescent-shaped chambers, a plurality of radially arranged pockets in the stator and dividing the interior thereof into a plurality of chambers, means for introducing explosive mixture into the said chambers, pistons slidably arranged in the pockets, cam means carried by the casing for reciprocating the pistons, a valve casing arranged in front of each pocket and opening out through the stator and in communication with the interior thereof, an outwardly opening spring pressed valve in each casing, the stator having recesses therein adjacent each valve casing forming compression spaces for the explosive mixture passing by the valves, ignition means carried by the casing adjacent a side thereof, exhaust means carried by the casing adjacent its other side.

4. An internal combustion motor comprising a hollow stationary shaft, a cylindrical stator fastened to the shaft, an oval-shaped casing enclosing the stator and rotatably supported on the shaft, said casing having its sides contacting the stator and its end portions spaced therefrom to form crescent-shaped chambers, a plurality of radially arranged pockets in the stator and dividing the interior thereof into a plurality of chambers, means for introducing explosive mixture into the said chambers, pistons slidably arranged in the pockets, cam means carried by the casing for reciprocating the pistons, a valve casing arranged in front of each pocket and opening out through the stator and in communication with the interior thereof, an outwardly opening spring pressed valve in each casing, the stator having recesses therein adjacent each valve casing forming compression spaces for the explosive mixture passing by the valves, ignition means carried by the casing adjacent a side thereof, exhaust means carried by the casing adjacent its other side, the ends of the casing having air chambers therein in communication with the atmosphere and said ends having oil chambers therein in communication with the pockets, means for introducing oil into one chamber and means for exhausting the oil from the other chamber.

5. An internal combustion motor comprising a hollow stationary shaft, a cylindrical stator fastened to the shaft, an oval-shaped casing enclosing the stator and rotatably supported on the shaft, said casing having its sides contacting the stator and its end portions

spaced therefrom to form crescent-shaped chambers, a plurality of radially arranged pockets in the stator and dividing the interior thereof into a plurality of chambers, means for introducing explosive mixture into the said chambers, pistons slidably arranged in the pockets, cam means carried by the casing for reciprocating the pistons, a valve casing arranged in front of each pocket and opening out through the stator and in communication with the interior thereof, an outwardly opening spring pressed valve in each casing, the stator having recesses therein adjacent each valve casing forming compression spaces for the explosive mixture passing by the valves, ignition means carried by the casing adjacent a side thereof, exhaust means carried by the casing adjacent its other side, an annular casing forming an exhaust chamber at one end of the main casing, means for connecting the same with the exhaust means, a cover plate for the exhaust chamber, means for supporting the same in a stationary manner from the hollow shaft, means for rotatably connecting the casing with the cover plate and exhaust pipes connected with the cover plate.

6. An internal combustion motor comprising a hollow shaft having one end closed and its other end adapted to be connected with a source of explosive mixture, a cylindrical stator of hollow construction connected with the shaft, an oval-shaped casing enclosing the stator and rotatably mounted on the shaft, radially arranged pockets in the stator, the walls of which divide the interior thereof into chambers, means for placing the chambers in communication with the hollow shaft, pistons slidably arranged in the pockets, cam means at the ends of the casing for reciprocating the pistons, valve casings carried by the stator and opening out through the circumference of the same and being in communication with the chambers therein, outwardly opening spring pressed valves in said casings, a number of the casings and valves being arranged in front of each pocket, chambers in the stator and opening out through the circumference thereof adjacent the valves, said stator having grooves in its circumference adjacent the valves spring actuated means for forming tight joints between the pistons and the walls of the pockets and between the outer portions of the pistons and the walls of the casing, ignition means adjacent one side of the casing and exhaust means adjacent the other side thereof.

7. An internal combustion motor comprising a hollow shaft having one end closed and its other end adapted to be connected with a source of explosive mixture, a cylindrical stator of hollow construction connected with the shaft, an oval-shaped casing enclosing the stator and rotatably mounted on the shaft, radially arranged pockets in the stator, the walls of which divide the interior thereof into

chambers, means for placing the chambers in communication with the hollow shaft, pistons slidably arranged in the pockets, cam means at the ends of the casing for reciprocating the pistons, valve casings carried by the stator and opening out through the circumference of the same and being in communication with the chambers therein, outwardly opening spring pressed valves in said casings, a number of the casings and valves being arranged 5 in front of each pocket, chambers in the stator and opening out through the circumference thereof adjacent the valves, said stator having grooves in its circumference adjacent the 10 valves, spring actuated means for forming tight joints between the pistons and the walls of the pockets and between the outer portions of the pistons and the walls of the casing, ignition means adjacent one side of the casing, 15 exhaust means adjacent the other side thereof, air chambers formed in the ends of the casing and in communication with the atmosphere and fins on exterior portions of the casing. 20

In testimony whereof I affix my signature.
ALEXANDER BLACKMAN.
